J. G. Vredenburgh, of Mount Vernon, N.Y.
Letters Patent No. 2213 Dated Oct. 31-1865.
Design for a Badge of the Union League.

The schedule referred to in these Letters Patent and making part of the same.

To all whom it may concern,

Be it known that J. G. Vredenburgh, of Mount Vernon, in the County of Westchester and State of New York, have invented a new design for a badge for the Union League of America, and I do hereby declare the following a full, clear, and exact description of the same, reference being had to the accompanying drawing forming a part of this specification and which represents a front or face view of my design.

The general form of my design is that of a circular plate having engraved, chased, painted, enameled or otherwise put upon its surface the several insignia shown in the drawing, viz: a buckled belt surrounding an inner circular ground, said belt having inscribed upon it at equal distances near the top of the circle the letters U.S.A. with a star interposed between each letter, and also one preceding the first letter and one succeeding the last letter. The end of the belt is made to hang over the main portion and has a small shield attached thereto. The circular ground within the belt bears the following insignia viz: on the left an arm with smoke or fire issuing from the same; in the centre a sword placed over an open Bible, behind which is the United States Flag; and to the right is shown a scroll intended to designate the constitution of the United States.

What I claim as my invention and desire to secure by Letters Patent is—

The design and configuration of the badge represented and described by the accompanying drawing and specification.
